DESIGN FOR A PATRIOTIC PHOTOGRAPH MOUNTING CARD

Lloyd V. Lamb, Seattle, Wash.

Application October 26, 1943, Serial No. 111,507

Term of patent 7 years

(Cl. D29—20)

To all whom it may concern:

Be it known that I, Lloyd V. Lamb, a citizen of the United States of America, residing at Seattle, King County, Washington, have invented a new, original, and ornamental Design for a Patriotic Photograph Mounting Card, of which the following is a specification, reference being had to the accompanying drawing, forming part thereof, wherein—

I claim:

The ornamental design for a patriotic photograph mounting card, as shown.
